UNITED STATES PATENT OFFICE.

WILLIAM POST ROLLO, OF HOLLAND PATENT, NEW YORK.

IMPROVEMENT IN FENCES.

Specification forming part of Letters Patent No. 125,761, dated April 16, 1872.

Specification describing a new and useful Improvement in Stone-Post Farm Fence, invented by WILLIAM P. ROLLO, of Holland Patent, in the county of Oneida and State of New York.

Figure 1 is a side view of a portion of my improved fence. Fig. 2 is a detail sectional view of the same, taken through the line *x x*, Fig. 1.

Similar letters of reference indicate corresponding parts.

My invention has for its object to furnish an improved farm-fence, designed for line and other permanent fences, which shall be strong and durable, and at the same time neat, tasteful, and substantial in appearance; and it consists in the stone-post fence constructed as hereinafter more fully described.

A is the foundation or base of the post, which is built of common stone upon a level or prepared surface, and from one and a half to four feet square, as the firmness of the soil and the required height of the post may require. The foundation *A* is leveled up to the bottom board or picket-rail *B*, allowance being made for the settling of the post, and it is then banked up. The bottom board or rail *B* is then arranged upon the foundation *A*, and the upper part *C* of the post is then built up to the required height with selected blocks of stone, the bottom board or lower picket-rail being thus anchored in the center of the post. The top boards or upper picket-rails *D* are placed end to end in grooves formed in the top of the posts *A C* to receive them, and are connected by ties with a grip.

In the case of a board fence the top boards *D* are covered and strengthened by a board, *E*, nailed to their top edges. The top and bottom boards *D B* are connected and strengthened between the posts *A C* by ties or cross-bars *F*, one or more of which, when the distance between the posts *A C* is long, may extend to the ground, as shown in Figs. 1 and 2. The intermediate boards *G* are attached to the ties *F*. When a high fence is required the ties *F* may be extended upward, and may have additional boards *H* attached to them. When bar-posts *I* are required their upper ends may be sustained in place by being attached to the top board or picket-rail *D*, as shown in Fig. 1.

When a picket-fence or a close board-fence is required the pickets or boards are attached to the bottom and top boards or rails *B D*, the ties serving as a part of said boards or pickets.

Having thus described my invention, I claim as new and desire to secure by Letters Patent—

The combination of the stone posts *A C*, anchored bottom board or picket-rail *B*, top board or picket-rail *D*, and ties *F*, with each other, whether intermediate boards *G* or vertical pickets or boards be used, substantially as herein shown and described, and for the purposes set forth.

WILLIAM POST ROLLO.
